CLAIM

The ornamental design for a saliva testing cassette as shown and described.

DESCRIPTION

FIG. 1 is a front elevational view of a saliva testing cassette showing my new design;

FIG. 2 is a left side elevational view thereof;

FIG. 3 is a bottom plan view thereof;

FIG. 4 is a top plan view thereof;

FIG. 5 is a rear elevational view thereof;

FIG. 6 is a right side elevational view thereof; and,
FIG. 7 is a bottom, front and left side perspective view thereof.

The broken lines in the figures show portions which form no part of the claimed design.
